UNITED STATES PATENT OFFICE.

MARSHMAN W. HAZEN, OF NEW YORK, N. Y., ASSIGNOR TO CORONA TYPEWRITER COMPANY, INCORPORATED, A CORPORATION OF NEW YORK.

RIBBON MECHANISM.

1,121,097.

Specification of Letters Patent. Patented Dec. 15, 1914.

Original application filed June 23, 1908, Serial No. 439,967. Divided and application filed June 3, 1909, Serial No. 499,875. Renewed October 8, 1914. Serial No. 865,772.

To all whom it may concern:

Be it known that I, MARSHMAN W. HAZEN, a citizen of the United States, and a resident of New York, county and State of New York, have invented certain new and useful Improvements in Ribbon Mechanisms, of which the following is a full, clear, and exact description.

This invention relates more particularly to the ribbon mechanism of visible front-strike typewriting machines, and is a division of my pending application, Sr. No. 439,967, filed June 23, 1908.

The primary objects of the invention are to provide simple and efficient means whereby the ribbon may be properly held adjacent to the face of the platen and so operated that it will be automatically moved away from the printing point immediately after the printing takes place; and to provide means whereby the ribbon is adapted to be variously adjusted relatively with respect to the platen so that the ribbon may have a plurality of colors thereon any one of which may be readily placed in operative position for changing the color of the writing.

Another object of the invention is to provide a simple and efficient machine in which the ribbon mechanism may be mounted upon the carriage support in such a way that the carriage support may be folded over above the keyboard without at all interfering with the operative parts of the machine, so that as soon as the support is again placed in position for use, the ribbon mechanism may be properly operated through the key-levers.

A further object of the invention is to provide simple and efficient means whereby the ribbon may be made to move in either direction across the machine, and to provide means whereby substantially the entire surface of the ribbon may be utilized.

With these and other objects in view, the invention will be hereinafter more particularly described with reference to the accompanying drawings, which form a part of this specification, and will then be pointed out in the claims at the end of the description.

In the drawings, Figure 1 is a longitudinal section of one form of machine embodying my invention, showing part of the mechanism in elevation. Fig. 1^a is a fragmentary vertical section showing one of the

corner posts or slides for the carriage and 55 the guide for said slide. Fig. 2 is a detail inverted plan of the carriage, support and mechanism mounted thereon detached from the machine. Fig. 3 is a fragmentary front elevation of the upper part of the machine, 60 showing in elevation, the means for vibrating the ribbon adjacent to the printing point. Fig. 4 is a fragmentary inverted plan showing a part of the means for adjusting the movement of the ribbon. Fig. 65 5 is an enlarged elevation, partly in section, of a part of the ribbon operating mechanism. Fig. 6 is an enlarged section, partly in elevation, of one of the ribbon spools; and Fig. 7 70 is a fragmentary sectional plan showing the worm and worm gear for rotating the ribbon spools.

The frame 10 may be of the usual or of any preferred construction, and extending transversely thereof are a plurality of rods 75 11 to which the key-levers 12 are pivoted, and these key-levers form a part of a universal or standard keyboard and at their inner ends may be connected by links 13 to the type-bars or carriers 14. These type-bars 14 80 may be pivoted to a bracket 15 at one of their ends and at their other ends may have type-heads 16 on which are a plurality of characters indicating the upper case, the lower case and the figures, and these type- 85 heads are adapted to engage the work sheet held about a platen 17 which may be supported to rotate in a carriage 18, the latter being movable lengthwise of its bed 19. The carriage may be operated by any suitable mechanism and may have its support adapted to be folded over, as shown in dotted lines in Fig. 1, all of which may be of the usual or of any preferred construction.

To operate the ribbon and to adapt the 95 same to be shifted with respect to the type so that a ribbon having more than one color may be employed or the entire surface of the ribbon used, a plurality of ribbon spools 20 and 21 are arranged upon the carriage bed 100 so as to be elevated therewith. These spools are each held to rotate with or independently of a sleeve 22. A shaft or spindle 23 passes through each sleeve and these spindles are fixed to the arms 24, the latter being pivotally held to bars 25 located on opposite sides of the machine and forming a part of a vertically movable support. Each sleeve is

threaded at its upper end, as at 26, on which is arranged a thumb-nut 27 which is adapted to engage the flange 28 of the spool and force a part of the same into engagement with the shoulder 29 of the sleeve 22, whereby the spool may be made to rotate with the sleeve or independently thereof, according to whether the thumb-nut 27, Figs. 5 and 6, is tightened or released. The ribbon 30 is held between the movable flange 28 of the spool, and the stationary flange 31, and one end of said ribbon may be fastened to the sleeve part 32 of each spool. Each flange 31 is supported by a bracket 33 secured to one of the arms 24, and is provided with a ribbon guide 34. This guide 34 is in the form of a loop having a slot at one side, as at 35, through which the ribbon may be passed, and said loop may be arranged in a substantially vertical plane. Each sleeve is provided with a gear 36 which is engaged by a worm 37 mounted to rotate in a bracket 38, and on the spindle or shaft 39 of each worm is a ratchet wheel 40 which is engaged by a pawl 41 carried by the upper end of each lever or arm 42, so that when said lever is moved, the pawl will be made to impart a step-by-step movement to the worm and the ribbon whenever any of the key-levers are depressed, as will be presently described, the said ratchet wheels each being engaged by a spring-pressed pawl or detent 43 to prevent the ratchet wheel from moving except in one direction. As will be seen, the gears 36 are both moved when the ratchet wheels 40 are operated through the movement of the arms or levers 42 but on the return movement of the levers, and only that spool is operated in which the nut 27 has been tightened to cause the spool to rotate with the sleeve 22, the ribbon thereby being made to move in either direction according to which spool is loose on the sleeve and the other tightened.

The ribbon extends inwardly to the front part of the platen as shown best in Fig. 2, and is passed through the loop or slotted portion 44 formed in the end of a vibratory arm 45. This arm 45 is pivoted at 46 to the inner edge of the carriage bed, and has a tooth or shoulder portion 47 which is engaged by one end of a bell-crank or angular lever 48, and said arm is normally forced in one direction against the action of the lever 48 by means of a spring 49 which is attached to the lever at one end and to the carriage bed at the other. The lever 48 is pivoted at 50, and has its arm 51 adapted to strike a stop or projection 52 and its outer end arranged in the path of a movable slide or device 53 carried by the transverse bar 54 of a rocking frame of which the arms 42 form a part and which are rigidly connected to said bar. This device is slidably held upon the bar 54, and is limited in its move-
ment along the same in one direction by a collar or part 55, and in the other direction by a pin 56 carried by said bar. The device 53 is substantially U-shaped in form, and is provided with a downwardly projecting lug 57 through which is passed a screw 58 to hold the same to the transverse bar 54. The device 53 is provided with a projecting part 59 serving as a handle to move the slide, and on the outer surface thereof has a part forming a cam surface 60 which may be integral with said device or slide. By moving the device to cause the cam portion 60 to engage the end of the arm 51 of the lever 48, the throw of said lever 48 may be varied and thereby the movement of the vibratory arm 45 carrying the ribbon. The movement of the device is arranged to adapt the ribbon to print two different colors, so that by moving the slide one way its extreme throw will cause one part of the ribbon to be engaged by the type, and if moved in the other direction the other color of the ribbon may be used, and at each movement of any of the key-levers to be described later, the said device will vibrate the ribbon laterally for printing purposes, and as soon as the key-levers are released, the spring 49 will return the vibratory arm to its normal position entirely free and below the printing point to permit the writing to be seen immediately. By sliding the device 53 between any of the two extremes, a graduated movement of the ribbon may be given, thereby permitting the entire surface of the ribbon to be used and thus materially saving the wear of the same, the end of the arm 51 of the lever 48 being so positioned that the slide or device 53 will have a certain movement before engaging the lever 48 in order that the vibratory arm 45 may always be returned by the spring 49 below the printing point whatever the position of the device 53 may be.

The bar 54 is held in the upper end of the arms or levers 42 which are pivoted on opposite sides of the machine to a transversely-extending rod or bar 61; and in the upper end of each of said arms 42 is a vertical slot 62. A bell-crank or angular lever 63 is pivoted at 64 to a part of the machine frame 115 on each side thereof, and has one end, as by a screw 65, guided in the slot 62 of one of the arms 42 and its other end connected by a link or rod 66 to a universal bar 67. This universal bar 67 extends transversely of the 120 machine over each key-lever, so that as each key-lever is depressed, it will raise the bar 67 and move both of the bell-crank levers 63 on their pivots 64, and by means of the shoulder screws 65 in the slots 62 of the arms 42 will throw the bar 54 outward and thereby move the device 53 to operate the bell-crank lever 48 and through it vibrate the arm 45 and ribbon, and on the return movement of the arms 42 the pawls 41 car- 130

ried thereby will impart a movement to the ratchet wheels 40 to shift the position of the ribbon lengthwise of the platen and in a direction depending on which nut 27 is 5 tightened as already explained.

The levers or arms 42, Fig. 1, may be forced inward by the springs 68 which are held at one end to the rear part of the frame and engage the arms 42 at their free ends.

10 An adjusting screw 69 is adapted to engage each spring 68 and serves to vary the pressure of the springs against the levers 42, and by means of the bell-crank levers 68 and links 66 the universal bar 67 will be forced 15 against the action of the key-levers with any desired pressure. This action of the springs 68 not only serves to permit the force required to operate the type-bars to be changed, but they serve to restore the type-bars and key-levers to their normal position, and if desired other springs for each key-lever may be dispensed with.

An arm 70 may be connected to the transverse rod 61 and this arm may be operated 20 by a shift lever 71 which is held to the transverse rod 72 of a suitable platen shift mechanism so that the carriage and platen as well as the ribbon mechanism may be moved vertically and maintained in operative coöperation with the key-levers whatever the vertical adjustment may be. When the carriage is folded over as shown in dotted lines in Fig. 1, to make the machine more compact, the ribbon spools and their 25 rotating mechanism as well as the bell-crank lever 48 and arm 45 for vibrating the ribbon laterally will be folded also, which will carry the ratchet wheels 40 away from the pawls 41, and the bell-crank lever 48 away 30 from the device 53 of the rocking frame, but as soon as the carriage is restored to its normal working position, the mechanism for moving the ribbon lengthwise of the platen and for vibrating the ribbon laterally 35 will be automatically placed in position to be operated by the key-levers. The rocking frame remains in operative relation with the key-levers at all times and by reason of the slots 62 in the arms 42, the said arms 40 may be moved vertically with the carriage and ribbon mechanism when the platen shift mechanism is operated.

While I have shown and described features of a typewriting machine other than 55 the ribbon mechanism, such features as are not claimed herein are covered in my pending application hereinbefore referred to, or in other divisional and co-pending applications.

60 From the foregoing it will be seen that simple and efficient ribbon mechanism is provided whereby the ribbon may have a plurality of colors thereon: that said ribbon is so operated that it will permit visible 65 writing and may have substantially its en-

tire surface used, thus materially increasing the life of the ribbon; that simple means is provided whereby the ribbon may be moved in either direction, and that said mechanism is so constructed that a part thereof may be 70 folded over above the keyboard, to cause the machine to occupy much less space than when in use.

Having thus described my invention, I claim as new and desire to secure by Letters 75 Patent:—

1. In a typewriting machine, the combination with a support, of a carriage movably held on said support, a platen mounted on the carriage, a ribbon held to move in front of the platen, an arm engaging the ribbon for moving the same laterally to and from the printing point, a plurality of key-levers, a transverse bar adapted to be moved by the key-levers, a device longitudinally adjustable on the transverse bar, and means operated by said device whereby the arm engaging the ribbon may be vibrated and its throw varied according to the position of said device. 80

2. In a typewriting machine, the combination with a support, of a platen mounted on the support, a ribbon held to move in front of the platen, an arm engaging the ribbon for moving the same laterally to and from 85 the printing point, a transverse bar having a bodily movement lengthwise of the machine, a device longitudinally adjustable on the transverse bar, and means operated by said device whereby the arm engaging the ribbon may be vibrated and its throw varied according to the position of said device. 90

3. In a typewriting machine, the combination with a support, of a carriage movably held on said support, a platen mounted on the carriage, a ribbon adapted to move along the platen, a pivotally held arm engaging the ribbon and adapted to move the same laterally, a bell-crank lever adapted to engage one end of the arm to force the same 100 in one direction, a spring normally forcing the arm in the opposite direction, a transverse bar, a plurality of key-levers, a universal bar, means supporting the universal bar whereby the same may be moved as each 105 key-lever is depressed, a movable device held upon the transverse bar having a cam surface on one side thereof and adapted to engage one end of the bell-crank lever whereby the lateral movement of the ribbon may be 110 quickly varied to adapt the ribbon to have any part of its surface subjected to engagement by the type. 115

4. In a typewriting machine, the combination with a support, of a carriage movably held on said support, a platen mounted on the carriage, a ribbon adapted to move along the platen lengthwise thereof, a pivotally held arm engaging the ribbon, and adapted to move the same laterally, a bell- 120 125

crank lever engaging one end of the arm, a transverse bar, a plurality of key-levers, means supporting the said bar whereby the same may be moved as each key-lever is depressed, and a movable device held upon the bar and having a cam surface on one side thereof and adapted to engage one end of the bell-crank lever whereby the lateral movement of the ribbon may be quickly varied.

5. In a typewriting machine, the combination with a support, of a carriage movably held on said support, a platen mounted on the carriage, a ribbon adapted to move along the platen lengthwise thereof, a pivotally held vibratory arm engaging the ribbon and adapted to move the same laterally, a bell-crank lever adapted to engage the arm, a transverse bar, a plurality of key-levers, means for moving said bar as each key-lever is depressed, and a movable device held upon the bar adapted to engage the bell-crank lever and vary the throw of the ribbon according to its position.

6. In a typewriting machine, the combination with a support, of a carriage movably held on said support, a platen mounted on the carriage, a ribbon adapted to move along the platen lengthwise thereof, a pivotally held arm engaging the ribbon and adapted to move the same laterally, a transverse bar, a bell-crank lever adapted to engage one end of the arm to force the same in one direction, a spring normally forcing the arm in the opposite direction, and a device longitudinally adjustable on said transverse bar engaging said bell-crank lever.

7. In a typewriting machine, the combination of a support, a carriage movably held on said support, a platen mounted on the carriage, a ribbon movable lengthwise of the platen, a vibratory arm having a slotted portion through which the ribbon passes, a transverse bar, means for moving the transverse bar, stops arranged on the transverse bar, a slide having a finger piece adjustable along the bar and having its rear part provided with an inclined cam surface and limited in its movement along said bar by means of the stops, a screw for holding the slide to the bar, and means adapted to be operated by the slide to move the vibratory arm when said bar is moved.

8. In a typewriting machine, the combination of a carriage, a platen mounted on the carriage, a ribbon movable lengthwise of the platen, a vibratory arm having a slotted portion through which the ribbon passes, a transverse bar, means for moving the transverse bar, a device adjustable along the bar and having its rear provided with a cam surface, and means adapted to be operated by said device for moving the vibratory arm when said bar is moved.

9. In a typewriting machine, the combination of a carriage, a platen mounted on the carriage, a ribbon movable lengthwise of the platen, a vibratory arm having a slotted portion through which the ribbon passes, a transverse bar, means for moving the transverse bar, a slide having a finger piece adjustable along the bar and having its rear provided with a cam surface, and means adapted to be operated by the slide to move the vibratory arm when said bar is moved.

nation of a carriage, a platen mounted on the carriage, a ribbon movable lengthwise of the platen, a vibratory arm having a slotted portion through which the ribbon passes, a transverse bar, means for moving the transverse bar, a slide having a finger piece adjustable along the bar and having its rear provided with a cam surface, and a bell-crank lever adapted to be operated by the slide to move the vibratory arm when said bar is moved.

10. In a typewriting machine, the combination of a ribbon, a transverse bar, a slide longitudinally adjustable on said bar and having a cam surface on a part thereof, and means operated by the slide whereby a vibratory movement may be given the ribbon differing in degree according to the position of said slide.

11. In a typewriting machine, the combination with a ribbon, of a bodily movable bar, a device longitudinally adjustable on said bar, and means operated by the device whereby a vibratory movement may be given the ribbon differing in degree according to the position of said device.

12. In a typewriting machine, the combination with a ribbon, of a vibratory arm engaging the ribbon, a transverse bar, a device longitudinally adjustable on said bar and having a cam surface on one side thereof, and means operated by the device for varying the throw of the arm and thereby the ribbon.

13. In a typewriting machine, the combination of key-levers, a platen carriage foldable forward into compact relation to another part of the machine and to an abnormal position when not in use, and a ribbon mechanism including ribbon spools mounted to fold with the carriage, said mechanism comprising means adapted to be actuated normally by the key-levers, and means movable with the platen carriage in its folding movement.

14. In a typewriting machine, the combination of key-levers, a platen carriage foldable into substantially overhanging relation to the key-levers or the type-bars, a carriage tension mechanism for actuating said platen carriage, a ribbon mechanism including ribbon spools mounted to fold with the carriage, said mechanism comprising means adapted to be actuated normally by the key-levers, said last-mentioned means being separable to adapt the carriage and ribbon spools to be folded with the carriage.

15. In a typewriting machine, the combination of key-levers, a platen carriage foldable into substantially overhanging relation to the key-levers, a ribbon mechanism including ribbon spools mounted to fold with the carriage and located on opposite sides of the machine to adapt the ribbon to move in front and along the platen, means for mov-

ing the carriage vertically, said ribbon mechanism comprising means adapted to be actuated normally by the key-levers, and means movable with the platen carriage in its folding movement, said ribbon mechanism means being adapted for cooperation with the key-actuated means of said mechanism only when the carriage is restored to a working position.

16. In a typewriting machine, the combination of a platen carriage foldable forward into compact relation to another part of the machine and to an abnormal position when not in use so as to occupy less space than when in a working position, two spools mounted to fold with the carriage, means mounted to fold with the carriage for operating said spools to cause the ribbon to pass from one side of the machine to the other, key-actuated means cooperating with the ribbon means whereby said latter means may be operated, said key-actuated means being unaffected by the folding adjustment of the carriage and adapted to be engaged automatically when the carriage is shifted from a folded position into a position for use.

17. In a typewriting machine, the combination of a platen carriage foldable into substantially overhanging relation to the keys or type-bars, ribbon spools mounted on opposite sides of the machine and adapted to fold with the platen carriage, mechanism for rotating the spools and adapted to remain in coöperative relation with said spools, and key-actuated means adapted to coöperate with the foldable parts of the ribbon operating means when the carriage is in working position.

18. In a typewriting machine, a platen carriage foldable forward into compact relation to another part of the machine and to an abnormal position when not in use so as to occupy less space than when in a working position, ribbon mechanism including two spools, a worm gear mounted to rotate each spool, a worm engaging each worm gear, a ratchet wheel rotatable with the worm, a pawl tending to hold the ratchet wheel against movement except in one direction, all of which are mounted to fold with the carriage, and key-actuated means adapted to rotate the ratchet when the platen carriage is in its normal position and to be separable therefrom when the carriage is in a folded position.

19. In a typewriting machine, a platen carriage shiftable into compact relation to another part of the machine and to an abnormal position when not in use so as to occupy less space than when in a working position, ribbon mechanism including two spools, a worm gear mounted to rotate each spool, a worm engaging each worm gear, a ratchet wheel rotatable with the worm, a

pawl tending to hold the ratchet wheel against movement except in one direction, all of which are mounted to shift with the carriage in its compact movement, and key-actuated means adapted to rotate the ratchet wheel when the platen carriage is in its normal position only.

20. In a typewriting machine, a platen carriage foldable forward into compact relation to another part of the machine and to an abnormal position when not in use so as to occupy less space than when in a working position, two spools, a worm gear mounted to rotate each spool, a worm engaging each worm gear, a ratchet wheel rotatable with the worm, a pawl tending to hold the ratchet wheel against movement except in one direction, all of which are mounted to fold with the carriage in its compact movement, means for vibrating the ribbon, and key-actuated means adapted to rotate the ratchet wheel when the platen carriage is in its normal position.

21. In a typewriting machine, a carriage bed shiftable forward into compact relation to another part of the machine and to an abnormal position when not in use so as to occupy less space than when in a working position, a platen carriage movable endwise of the carriage bed and shiftable therewith, ribbon mechanism mounted to shift with the carriage in its forward compact movement, and key-actuated means for said ribbon mechanism, the said ribbon mechanism being movable with the carriage bed into and out of engagement with an element of the key-actuated means.

22. In a typewriting machine, a carriage bed, a platen carriage adapted to travel thereon, a foldable support for said bed, a spindle mounted on said support at each side thereof, a ribbon spool mounted upon each spindle, means mounted adjacent to each spindle for rotating the spools to cause the ribbon to pass from one spool to the other, and key-actuated means adapted to operate the spool rotating means only when the carriage is in its normal working position.

23. In a typewriting machine, a carriage bed, a platen carriage adapted to travel thereon, a support for said bed and carriage, two spools mounted on opposite sides of the machine on the support and foldable with the carriage bed, a worm gear for rotating each spool, a worm in mesh with each gear, a ratchet wheel for rotating each worm, a pawl tending normally to hold the ratchet wheel against movement except in one direction, a second pawl for operating each ratchet wheel and key-actuated means carrying the pawls for operating the ratchet wheels when the carriage bed and platen carriage are in their normal working position.

24. In a typewriting machine, a carriage bed shiftable into compact relation to another part of the machine and to an abnormal position when not in use so as to occupy less space than when in a working position, a platen carriage adapted to travel thereon, a support for said bed and carriage, two spools mounted on opposite sides of the machine on the support and shiftable with the carriage bed to partake of its compact movement, a worm gear for rotating each spool, a worm in mesh with each gear, a ratchet wheel for rotating each worm, a pawl tending normally to hold the ratchet wheel against movement except in one direction, a second pawl for operating each ratchet wheel, and key-actuated means carrying the pawls for operating the ratchet wheels when the carriage bed and platen carriage are in their normal working position. 70
25. In a typewriting machine, a carriage bed, a platen carriage adapted to travel thereon, a foldable support for the platen carriage, ribbon mechanism mounted upon the support and foldable with the carriage bed, and a rocking key-actuated frame having means for coöperation with the ribbon mechanism. 75
26. In a typewriting machine, a carriage bed, a platen carriage adapted to travel thereon and shiftable with the bed into compact relation to another part of the machine and to an abnormal position when not in use so as to occupy less space than when in a normal working position, a support for the platen carriage, ribbon mechanism mounted upon the support and shiftable with the carriage bed to partake of its compact movement and to be inverted during such movement, and a rocking key-actuated frame having means for coöperation with the ribbon mechanism. 80
27. In a typewriting machine, a carriage bed, a platen carriage adapted to travel thereon, a foldable support for the bed, ribbon mechanism including two spools mounted upon the support and foldable therewith, said mechanism including ratchet wheels, typewriter keys, and a rocking frame adapted to be operated at all times by the keys and having pawls adapted to engage the ratchet wheels when the carriage and support are in their normal working position and to be separated therefrom when the carriage and bed are moved to a folded position. 85
28. In a typewriting machine, a carriage bed shiftable into compact relation to another part of the machine and to an abnormal position when not in use so as to occupy less space than when in a working position, a platen carriage adapted to travel thereon, a support for the bed, ribbon mechanism including two spools mounted upon the support and shiftable with the bed during its 90
- compact movement, said mechanism including ratchet wheels, and a rocking frame having pawls adapted to engage the ratchet wheels when the carriage and support are in their normal working position and to be separated therefrom when the carriage and bed are shifted to a compact position. 95
29. In a front-strike typewriting machine, a carriage bed movable into compact relation to another part of the machine and to an abnormal position when not in use, a traveling carriage thereon partaking of the compact movement of the bed so as to occupy less space than when in a working position, means for moving the carriage bed vertically, ribbon mechanism, and key-actuated means adapted for movement vertically and to maintain coöperative relation to the ribbon mechanism to operate said mechanism. 100
30. In a front-strike typewriting machine, a carriage bed foldable forward over the keys, a traveling carriage thereon, devices for moving the carriage bed vertically, ribbon mechanism shiftable with the carriage bed, and key-actuated means adapted for movement vertically and to maintain a coöperative relation to said ribbon mechanism to operate said mechanism. 105
31. In a front-strike typewriting machine, a carriage bed shiftable forward into compact relation to another part of the machine and to an abnormal position so as to occupy less space than when in a working position, a traveling carriage thereon, means for moving the carriage bed vertically, ribbon mechanism shiftable with the carriage bed, spacing and type-bar keys, and means coöperating with all the keys and the ribbon mechanism to operate said mechanism as the keys are operated. 110
32. In a front-strike typewriting machine, a foldable support for a platen carriage, ribbon mechanism including ratchet wheels mounted on the support, a rocking frame coöoperating with the keys and actuated thereby, and pawls mounted on the rocking frame adapted to engage and operate the ratchet wheels, said ratchet wheels being separable from the pawls when the support is folded. 115
33. In a front-strike typewriting machine, a platen carriage, a platen mounted on the carriage, a support for the carriage, a rocking frame, means for adjusting the platen carriage and frame vertically, key-levers, a universal bar actuated thereby, bell-crank connections between the universal bar and the rocking frame, and ribbon mechanism mounted upon the support and shiftable therewith and adapted to be operated by the rocking frame when in normal working position. 120
34. In a front-strike typewriting machine, a platen carriage, a platen mounted 125

on the carriage, a support for the carriage along which the latter travels, a rocking frame having pawls thereon, key-levers, spacing levers, a universal bar coöperating with the key-levers and spacing levers, means for elevating the platen carriage and the rocking frame, and ribbon mechanism mounted upon the support including ratchet wheels adapted to be operated by the rocking frame at different points in the elevation of the platen carriage.

35. In a typewriting machine, key-operated type-bars, a platen carriage normally in the path of the type-bars and adapted to be folded to a position out of coöperative relation to said type-bars, key-actuated levers, and a ribbon mechanism comprising a plurality of elements including ratchets and pawls, the latter of which are normally in coöperative relation to the key-actuated levers, and the ratchets are foldable with said platen carriage when it is adjusted into and out of the aforesaid coöperative relation to the key-operated levers.

25 36. In a typewriting machine, a keyboard, type bars, a platen carriage adapted to lie in the path of said type-bars and shiftable forward from said position into overhanging relation to the keyboard so as to occupy less space than when in use, a ribbon mechanism, and means for actuating said mechanism, said mechanism comprising coöperative devices which are separable when said carriage is in a position out of the path of the typé-bars.

37. In a typewriting machine, the combination with key-actuated levers and type carriers, of a platen normally in the path of said type carriers and shiftable into compact relation to another part of the machine and to an abnormal position when not in use, and ribbon mechanism shiftable with the platen and coöperating with the keys to operate the ribbon when the platen is in a working position only.

38. In a typewriting machine, the combination with key-levers and type carriers operated by said key-levers, of a carriage, a platen mounted on the carriage and normally in the path of said type carriers and shiftable with the carriage into compact relation to another part of the typewriter and to an abnormal position when not in use, and ribbon mechanism shiftable with the carriage in its compact movement and coöperating with the key levers to operate the ribbon when the platen is in a working position only.

39. In a typewriting machine, key-levers, type-bars operated by said key-levers, a vertically movable carriage, a platen mounted on said carriage and normally in the path of said type-bars and bodily movable into overhanging relation to the key-levers to occupy less space than when in use, and ribbon

mechanism mounted to shift with the carriage and platen and having means coöperating with the key-levers and operated to move the ribbon only when the platen is in a working position.

40. In a typewriting machine, key-levers, type-bars operated by said key-levers, a vertically movable carriage, a platen mounted on said carriage and normally in the path of said type-bars and bodily shiftable forward into compact relation to another part of the machine and to an abnormal position to occupy less space than when in use, ribbon mechanism mounted to shift with the carriage and platen and having means coöperating with the key-levers and operated to move the ribbon only when the platen is in a working position, and means for vibrating the ribbon also shiftable with the carriage.

41. In a typewriting machine, the combination with key-levers, of a carriage, a support for said carriage, a platen mounted on the carriage and bodily shiftable into compact relation to another part of the machine and to an abnormal position to occupy less space than when in use, and a separable ribbon mechanism a part only of which is shiftable with the platen, and the other part of said mechanism being independent of said shifting movement and coöperating with the key-levers to move the ribbon only when the platen and carriage are in a working position.

42. In a typewriting machine, the combination of key-levers, type-bars operated by said key-levers, a carriage, a support for said carriage, a platen mounted on the carriage and normally in the path of said type-bars and bodily shiftable forward toward the key-levers into compact relation to another part of the typewriter and to an abnormal position when not in use so as to occupy less space than when in a working position, and a separable operating mechanism, a part only of which is shiftable with the platen, and the other part of said mechanism being independent of said shifting movement and coöperating with the key-levers to move the ribbon only when the platen and carriage are in a working position.

43. In a front strike typewriting machine, the combination with a vertically movable carriage, of a platen mounted on said carriage, a vertically movable and rocking frame, pivotally held bell-crank levers connected to said rocking frame, a universal bar, links connecting the universal bar to the bell-crank levers, spacing levers adapted to operate the universal bar, and ribbon mechanism operatively connected to the rocking frame and operated thereby to shift the ribbon as each key-lever is moved.

44. In a typewriting machine, the com-

- combination with a vertically movable carriage, of a platen mounted on said carriage, means for imparting a step-by-step movement to the carriage, a vertically movable and rocking frame, pivotally held bell-crank levers connected to said rocking frame, a universal bar, links connecting the universal bar to the bell-crank levers, spacing-levers adapted to operate the universal bar, and ribbon mechanism operatively connected to the rocking frame and operated thereby to shift the ribbon lengthwise and laterally as each key lever is moved. 45. In a typewriting machine, the combination with a movable carriage, of a platen mounted on the carriage, means for shifting the carriage vertically, arms movable vertically with the platen, pawls carried by the arms, key-levers, means including bell-crank levers for operatively connecting the key-levers to the arms for operating said arms, and ribbon mechanism including ratchet wheels adapted to be operated by the pawls. 46. In a typewriting machine, the combination with a movable carriage, of a platen mounted on the carriage, means for shifting the carriage vertically, arms movable vertically with the platen, pawls carried by the arms, key-levers, means including bell-crank levers for operatively connecting the key-levers to the arms for operating said arms, and ribbon mechanism including ratchet wheels adapted to be operated by the pawls. 47. In a front strike typewriting machine, the combination with a carriage and means for moving the same vertically, of ribbon mechanism mounted to move with the carriage, a frame forming a part of said mechanism and having vertically movable arms, and means for operating the arms whatever their position to operate the ribbon mechanism. 48. In a typewriting machine, the combination with a carriage and means for moving the same vertically, of ribbon mechanism mounted to move with the carriage, a frame forming a part of said mechanism and having vertically movable arms, and means for operating the arms whatever their position to impart a lengthwise and lateral movement to the ribbon. 49. In a typewriting machine, the combination of a carriage bed, a carriage adapted to move along said bed, a bell-crank lever pivotally mounted under the bed, key-levers, a rocking frame co-operating with the key-levers and adapted to engage a part of said bell-crank lever to operate the same when the key-levers are operated, a vibratory arm having a part thereof engaged by said bell-crank lever whereby said arm may be vibrated, a spring tending normally to return the vibratory arm to its normal position below the printing point, a support, spools mounted upon the support, means for rotating the spools to cause the ribbon to pass from one side of the machine to the other, and means movable with the rocking frame adapted to operate one of the spools at each movement of the rocking frame through the depression of one of the key-levers. 50. In a typewriting machine, the combination of a carriage bed, a carriage adapted to move along said bed, a bell-crank lever pivotally mounted under the bed, key-levers, a rocking frame co-operating with the key-levers and adapted to engage a part of said bell-crank lever to operate the same when the key-levers are operated, a vibratory arm having a part thereof engaged by said bell-crank lever whereby said arm may be vibrated, a spring tending normally to return the vibratory arm to its normal position below the printing point, a support, spools mounted upon the support, and means movable with the rocking frame adapted to operate one of the spools at each movement of the rocking frame through the depression of one of the key-levers. 51. In a typewriting machine, the combination of a platen carriage, a platen mounted on said carriage and shiftable therewith into compact relation to another part of the machine and to an abnormal position when not in use so as to occupy less space than when in a working position, key-levers, and ribbon mechanism shiftable with the carriage and platen and co-operating with the key-levers to impart a lateral and lengthwise movement to the ribbon when the platen is in a working position only. 52. In a typewriting machine, the combination of a platen carriage shiftable forward into compact relation to another part of the machine and to an abnormal position when not in use so as to occupy less space than when in a working position, key-levers, and ribbon mechanism shiftable with the carriage and platen in their compact movement and co-operating with the key-levers to impart a lateral and lengthwise movement to the ribbon. 53. In a typewriting machine, the combination with a carriage and a platen mounted on said carriage, of a bed along which the carriage is adapted to travel, a bell-crank lever pivotally held to and under the carriage bed, key-levers, means actuated by the key-levers adapted to move the bell-crank lever as each key is depressed, means for supporting a ribbon and for moving the same lengthwise, a vibratory arm engaging the ribbon and adapted to move the same to and from the printing point, and means whereby the bell-crank lever may be made to operate said vibratory arm. 54. In a typewriting machine, the combination with a carriage and a platen mount-

ed on said carriage, of a bed along which the carriage is adapted to travel, a lever pivotally held to move horizontally under the carriage bed, key-levers, means actuated by the key-levers adapted to move said lever, a vibratory arm engaging the ribbon and adapted to move the same to and from the printing point, and means whereby the lever may be made to operate said vibratory arm.

55. In a typewriting machine, the combination with a carriage and a platen mounted on said carriage, of a bed along which the carriage is adapted to travel and shiftable into compact relation to another part of the machine and to an abnormal position when not in use, a bell-crank lever pivotally held to and under the carriage bed, key-levers, means actuated by the key-levers adapted to move the bell-crank levers as each key is depressed, means for supporting a ribbon and for moving the same lengthwise, a vibratory arm engaging the ribbon adapted to move the same to and from the printing point, and means whereby the bell-crank lever may be made to operate said vibratory arm.

56. In a typewriting machine, the combination with a carriage and a platen mounted on said carriage, of a bed along which the carriage is adapted to travel, and shiftable with the carriage into compact relation to another part of the machine, and to an abnormal position to occupy less space than when in use, key-levers, means for moving a ribbon lengthwise of the platen and means for moving the ribbon laterally, both of said means being shiftable with the carriage and bed and coöperating with the key-levers when the carriage is in its normal position.

57. In a visible typewriting machine, the combination of a universal keyboard having key-operated levers, type-bars operated by individual key-levers, a platen carriage, ribbon mechanism adapted to be operated by the key-levers when in a normal working position, means for shifting the platen and ribbon mechanism in a vertical direction, and a foldable support on which the ribbon mechanism and platen carriage are mounted, said support having the platen carriage normally in the path of the type-bars when in a working position and moving said carriage out of the path of the type-bars over

the keyboard and carrying therewith the ribbon mechanism in such folding movement to reduce the size and cubical dimensions of the machine for transportation purposes.

58. In a visible typewriting machine, the combination of a universal keyboard having key-operated levers, type-bars operated by individual key-levers, a platen carriage, ribbon mechanism adapted to be operated by the key-operated levers when in a normal working position, means for shifting the platen and ribbon mechanism in a vertical direction, and means whereby the platen carriage and ribbon mechanism may be brought out of the path of the type-bars into compact relation when not in use to reduce the size and cubical dimensions of the machine for transportation purposes.

59. In a front-strike typewriting machine, a universal keyboard having key-operated levers, type-bars each operated by one of said levers, a platen carriage, a foldable support for said platen carriage having one of its members movable into overhanging relation to the keyboard to reduce the size of the machine when not in use, means for shifting said foldable member in a vertical direction, and ribbon mechanism adapted to be operated by the key-operated levers when in a normal working position, said ribbon mechanism being mounted on said foldable member and partaking of its folding and shifting movement.

60. In a visible typewriting machine, key-levers forming a part of a universal keyboard, type-bars operated by said key-levers one for each key-lever, a vertically movable carriage, a platen mounted on said carriage and normally in the path of said type-bars and bodily movable with the carriage away from the type-bars into overhanging relation to the key-levers to occupy less space than when in use, and ribbon mechanism mounted to partake of the compact movement of the carriage and platen and having means coöperating with the key-levers and operated to move the ribbon only when the platen is in a working position.

This specification signed and witnessed this 29th day of May A. D. 1909.
